(57) **CLAIM**

The ornamental design for a medical bag and pump support, as shown and described.

DESCRIPTION

FIG. 1 is a perspective of a medical bag and pump support shown in combination with a backpack, a front flap of the backpack being shown in phantom;

FIG. 2 is a front view thereof;

FIG. 3 is a right side view thereof;

FIG. 4 is a top plan view thereof;

FIG. 5 is a rear view thereof;

FIG. 6 is a left side view thereof;

FIG. 7 is a bottom plan view thereof;

FIG. 8 is a perspective view of the medical bag and pump support with feet of the support in a deployed position and tabs on the feet shown in phantom;

FIG. 9 is a front view of the support of FIG. 8;

FIG. 10 is a right side view of the support of FIG. 8;

FIG. 11 is a top plan view of the support of FIG. 8;

FIG. 12 is a rear view of the support of FIG. 8;

FIG. 13 is a left side view of the support of FIG. 8;

FIG. 14 is a bottom plan view of the support of FIG. 8 with internal ribs of a base and the feet of the support shown in phantom;

FIG. 15 is a perspective view of the medical bag and pump support of FIG. 8 with the feet in a stowed position; and,

FIG. 16 is a bottom plan view of the support of FIG. 15 with the internal ribs shown in phantom.

The elements shown in phantom form no part of the claimed design.

1 Claim, 16 Drawing Sheets
